PROSTHETIC APPLIANCE

William L. Fitch, Santa Cruz, Calif., assignor to
Fitch and Sons, Inc., a corporation of California

Application June 17, 1946, Serial No. 677,268

2 Claims. (Cl. 3-12)

1

This invention relates to prosthetic appliances and more particularly to an artificial arm for use in case of an above-the-elbow amputation.

Prior art artificial arms usually failed to constitute a satisfactory substitute for the natural arm in two main respects. From a mechanical viewpoint, insufficient torque was available to rotate the forearm about the elbow to provide adequate facilities for lifting. From a cosmetic viewpoint, the prior art arms failed to simulate the swinging movement of a natural arm during walking, and from both a mechanical and a cosmetic viewpoint the prior art arms failed to provide continuous lifting movement and usually would have to be locked in the carrying position.

Objects of the invention are, therefore, to provide an artificial arm which will simulate as closely as possible the action of the natural arm, which will be of simple and durable construction, will be convenient to wear and easy to operate.

In accomplishing these and other objects of the present invention, I have provided improved details of structure, the preferred form of which is illustrated in the accompanying drawings, wherein:

Fig. 1 is a generally lateral elevational view of an artificial arm embodying the features of the present invention with the harness attached and the forearm partially flexed;

Fig. 2 is a generally anterior elevational view of the arm with harness attached, the forearm somewhat extended, and the finger hook omitted;

Fig. 3 is an enlarged fragmentary cross-sectional view, taken along a longitudinal mid-plane of Fig. 1; and

Fig. 4 is a view, similar to Fig. 3, of a modification of the present invention including a detachable elbow joint.

Fig. 5 is a fragmentary cross-sectional view similar to that of Fig. 3 showing a non-spherical modification of the elbow joint;

Fig. 6 is a generally anterior elevational view of the modification of Fig. 5 with the forearm extended;

Fig. 7 is a fragmentary view similar to that of Fig. 3 partially in cross-section, showing a modification of the elbow joint with the flexor and extensor cables in different planes; and

Fig. 8 is a fragmentary cross-sectional view similar to that of Fig. 3 showing a solid modification of the forearm elbow member with lost-motion connections for the operating cables.

Referring more particularly to the drawing:

Numeral 1 indicates generally the upper arm member of the prosthesis which is secured to the

2

body of the amputee by a harness generally indicated by the numeral 2. The harness consists of a rather wide band or strap 3 adapted to extend over the shoulder of the amputated arm. 5 This strap is generally made of leather but may be of any other suitable material. Attached, as by sewing at 4 and/or by riveting as at 5, to the end portions of the strap 3 is a connecting strap 6 adapted to extend beneath the armpit of the amputated arm. A belt 7, of leather or fabric, is adapted to extend beneath the upper portion of the other arm, passing over the back of the amputee and around his chest to buckle as at 8 to the strap 3. The belt 7 is fastened by sewing or other convenient means as at 9 to the posterior portion of the strap 3. This harness differs from the conventional harness particularly in that it dispenses with numerous supplementary straps and buckles usually found in the prior art.

20 The upper arm member 1 includes a lower portion 10, shown in Fig. 3 as made of wood. It may, however, be made of plastic, laminated fabric or metal, such as aluminum, to provide a lighter construction, so long as the material is of sufficient strength. The lower portion 10 is hollowed out as at 11 to form a receptacle preferably lined with leather 12 to receive the lower end of the stump. The outer surface of the portion 10 is covered with a layer 13 of pliable material, preferably leather, which is extended as at 14 to form a conventional bucket to receive the upper part of the stump. The bucket may be provided with lacings (not shown) to fasten more securely to the stump. The distal end of the upper arm member is hollowed out to form a generally spherical cavity 15, constituting the socket of a ball and socket type of elbow joint.

25 A forearm 16 is shown of a substantially unitary structure, preferably aluminum, which may be either sand cast, die cast or spun to provide at the proximal end thereof a portion 17 generally in the form of a sphere, constituting the ball of the ball and socket type elbow joint. The forearm member 16 may also be made of wood, plastic or laminated fabric or the like and the ball portion may be solid instead of hollow as shown. A conventional finger hook 18 is attached to the distal end of the forearm member 16 and is operated by means of a cable 19 connected to a separate harness (not shown) in a conventional manner.

30 To facilitate complete flexion without interference between the anterior surfaces of the upper arm and the forearm, said surfaces are bevelled or flattened in a known manner, as shown at 20

and 21, respectively. The forearm is pivoted to the upper arm at the elbow joint by means of a bolt or pin 22 passing through a lateral-medial diametral opening in the spherical portion 17 and fixed at its ends to supporting straps 23, preferably of metal, attached, as by screws 24, to the lateral and medial surfaces of the upper arm. To limit extension of the forearm to simulate the limitation of movement of a natural arm, a shoulder or step 25 is formed on the forearm adjacent to the elbow to abut a corresponding shoulder or step 26 formed on the upper arm (Fig. 3).

In the movement of a natural arm from the anatomical position hanging at the side to the carrying position, the forearm is flexed simultaneously with the movement of the upper arm. As the upper arm is moved from a position hanging at the side to the carrying position, the distance between a point on the body adjacent the spine of the scapula and a point on the proximal portion of the posterior of the upper arm is increased. Use is made of this increase in distance to actuate a mechanism to flex the forearm.

A flexible cable 27, preferably of stranded steel but conceivably of fiber, gut, or the like, is attached to the forearm by means of a lost motion connection adjacent the intersection of the spherical surface of the elbow ball 17 with the forearm proper. This connection includes an opening 28 through which the cable 27 passes into the hollow portion 29 of the forearm member. Adjacent the end of the cable lying within the portion 29 a bead 30, larger than the diameter of the opening 28, is fixed. When tension is applied to the cable 27, the bead 30 engages the periphery of the opening 28 and, thus, the tension on the cable is transmitted to the forearm in order to flex the latter. The opening 28 is preferably located in a longitudinal anterior-posterior mid-plane of the forearm.

The cable 27 lies on the anterior surface of the sphere 17 and enters the upper arm through an entrance opening 31 which is provided therein. The cable then extends in a generally supra-lateral direction either through a bore 32 cut directly through the material 10 or, if more convenient, along a path substantially between the cover 13 and the material 10, merging superficially through an exit opening 33 on the lateral aspect of the upper arm.

The cable 27 is surrounded by a flexible sheath 34, of known construction, made in the general form of a closely wound incompressible helix. The sheath 34 is anchored to the bucket by means of a loop 35 of leather, fabric or metal, fastened to the bucket at a point superior of the opening 33, and two internally threaded beads 36 abutting the loop on either side. The beads can be fixed at any desired point on the sheath, in a known manner, by virtue of the difference in pitch between the helix of the sheath, when compressed, and the internal threads on the beads. The proximal end of the sheath terminates at the point 37. The upper end of the cable 27 is anchored by any convenient means, such as a link 38 fastened to the harness strap 3 approximately adjacent the spine of the scapula of the amputee.

As the stump is raised toward the carrying position, the distance between the end of the cable attached to the anchor 38 and the termination 37 of the sheath increases. That is, the sheath 34 is drawn downwardly over the cable 27. In other words, the cable 27 is drawn upwardly relative to and through the sheath 34. From another point of view it may be said that as the upper arm is

flexed the cable 27 is pulled through the sheath 34 by the anchor 38. This action causes the bead 30 on the lower end of the cable 27 to engage the forearm beneath the opening 28 and thus flex or raise the forearm to carrying position. The cable 27 may hence be designated as a flexor cable. The opening 31 in the upper arm is so located as to lie within the same equatorial plane of the ball or sphere 17 as the opening 28 in the forearm, whereby, during the aforescribed movement of the cable 27, said cable lies along the circumference of a great circle of the sphere 17 and, thus, has no tendency to veer off this path. Since the cable acts always at the circumference of a circle of the sphere lying in a plane normal to the elbow axis and described about the elbow axis as a center, the torque exerted by it on the forearm is always applied at the same torque arm distance equal to the radius of the circle of the sphere. Assuming substantially constant tension on the cable 27 during the lifting of the arm, this means that the torque acting on the forearm is also substantially constant. In the embodiment illustrated, where the circle is a great circle of the sphere, the constant torque arm is the radius of the great circle, which is the radius of the sphere, and the torque acting on the forearm is the product of the radius of the sphere and the tension in the cable. This torque is obviously constant, if the tension in the cable is assumed to be constant.

Under certain circumstances it may be desirable to provide a torque arm of a length which varies during the flexion of the forearm. This may be accomplished by substituting for the circle of the sphere an arcuate surface, not circular about but generally concave about the elbow axis, having any desired curvature or shape such as an involute, evolute, cycloid, etc. The torque arm will be the perpendicular distance between the elbow axis and the line of action of the cable 27 as it leaves the arcuate surface, usually as a tangent. An example of such a variable-torque-arm construction is shown in Figs. 5 and 6 where elements corresponding to those in Fig. 3 are generally indicated by numerals greater by 100 than the corresponding numerals in Fig. 3. The upper arm 161 is provided with a generally spherical concavity 115 described about the axis of the elbow pivot pin 122 with a radius slightly greater than the longest radius vector of the nonspherical elbow ball 117 of the forearm 116. The flexor cable 127 and the extensor cable 139 are attached to the forearm 116 through a lost-motion connection with beads 138 and 141, respectively. In the position shown in Fig. 5, with the angle between the forearm and upper arm being about 90°, the cable 127 is acting at approximately a maximum torque arm, i. e. the length of the perpendicular from the axis of pin 122 to the line of action of the cable 127 is a maximum. Assuming that the force exerted on the cable 127 is substantially constant throughout the flexion and extension range of the upper arm, this arrangement would be advantageous in that it applies the maximum lifting torque to the forearm under the conditions when the torque exerted by the weight of the load on the hook or hand is a maximum. Since the cables 127 and 139 are not traveling on geodesics of the nonspherical ball 117, it is, of course, necessary to provide a guide means to prevent shifting of the cable such as groove 160 shown especially in Fig. 6 where cable 127 is broken away to better illustrate it.

It is obvious that any motion of the upper arm which increases the distance between the point 37 and the link 38 will cause flexing of the forearm. Because of this, the prosthesis simulates the behavior of a natural limb where the forearm can be flexed when the upper arm is either flexed or abducted or both flexed and abducted from the anatomical position.

To provide for extension of the forearm an extensor cable 39, similar to cable 27, is used. The distal end of cable 39 enters the hollow sphere 17 through an opening 40 on the posterior aspect thereof. The end is provided with a bead 41, similar to bead 36. The connection of the cable 39 to the sphere 17 has the same lost motion properties as the connection of cable 27. The cable 39 passes over the posterior surface of the sphere 17, enters the upper arm at an opening 42 on the posterior aspect thereof, and continues through a bore 43 which extends supra-medially either through the material 10 or slightly beneath the leather covering 13, in a manner complementary to that of bore 32. The cable emerges superficially through an opening 44 on the medial surface of the bucket 14 and continues supra-medially having its proximal end 45 anchored to a link 46, similar to link 39, which is fastened to the harness 3 at a point adjacent the anterior of the shoulder of the amputated arm. The cable 39 is surrounded by a flexible sheath 47, similar to sheath 34, which is anchored to the arm at 43 by means similar to loop 35 and beads 36.

It is apparent that when the upper arm is extended, the distance increases between a point, such as 48, on the anterior surface of the upper arm and a point, such as 45, on the harness. Use is made of this property of the geometry of the arm to actuate the extensor cable 39. By virtue of the arrangement of parts, the cable 39 is constrained to follow a particular path determined by the following elements: the cable anchor 46, the sheath anchor 48, the course of the sheath 47, the opening 42, the curvature of the sphere 17, the opening 43, and the bead 41. Two segments of this path are variable in length: (1) the segment between cable anchor 46 and sheath anchor 48, variable by extension or flexion of the upper arm and (2) the segment between the opening 42 and opening 43, variable by extension or flexion of the forearm. Since the sheath 47, as constructed and mounted, is substantially invariable in length, the remaining segments of the path of the cable are also invariable in length. Since the cable is inextensible, any increase in length of segment (1), such as that caused by extension of the upper arm must be accompanied by a corresponding decrease in the length of segment (2). This decrease can be accomplished only by pivoting of the forearm about the elbow axis in such a way that the opening 43 approaches the opening 42 and this pivoting is precisely the flexion of the forearm desired to simulate mechanically and cosmetically the action of a natural arm.

The extensor cable 39 is illustrated as lying on the circumference of the same great circle of the sphere 17 as the flexor cable 27. For proper coaction of the two cables, this implies that the increase in distance between anchor 36 and termination point 37 during flexion of the upper arm, say from anatomical position to carrying position, is equal to the increase in distance between sheath anchor 48 and cable anchor 46 when the upper arm is extended from carrying

position to anatomical position. In the event that this latter increase is smaller than the former, as is frequently the case on various amputees, this difference in increase is compensated for by causing the extensor cable 39 to travel not on a great circle path but on a small circle path of the sphere 17. The small circle chosen is of appropriate diameter to provide the desired difference in cable travel over that of the great circle course for the same angular rotation of the forearm. To accommodate the new position of the cable, the openings 40 and 42 would be shifted from the midplane of the arm although they would preferably remain in a common plane normal to the elbow axis. Since a cable following a small circle course will tend to assume a great circle course, which is the shortest distance between two points on a sphere, this tendency must be overcome by providing a circumferential groove along the chosen small circle in the surface of the sphere 17 in which the cable 39 will ride.

A modification showing the small-circle construction is illustrated in Fig. 7 where the spherical elbow forearm member 247 is provided with the flexor cable 227 traveling on the great-circle path, needing no guide on the surface of the sphere, while the extensor cable 239 lies in a groove 230 described on a small-circle path in a plane parallel to the great-circle path of cable 227.

Operation

To use the prosthesis of the present invention, the bucket 14 is placed over the stump of an amputated arm and the harness 2 is buckled in place on the amputee. The cables 27 and 39, in addition to moving the forearm, serve to hold the prosthesis to the amputee, thus eliminating the need for numerous straps found in prior art prostheses. As the stump and upper arm of the prosthesis are raised, for example, flexed toward carrying position, the cable 27, acting through the bead 30 bearing against the edge of opening 28, flexes the forearm. During this flexion of the forearm the edge of the opening 40 bears against the bead 41 and thus draws the cable 39 through the sheath 47. This motion of cable 39 is facilitated by the decrease in distance between the sheath anchor 48 and the cable anchor 46 consequent upon the flexing of the upper arm toward carrying position.

To extend the arm, as from carrying position toward anatomical position, the stump and upper arm member 1 of the prosthesis are extended, increasing the distance between the sheath anchor 48 and cable anchor 46 tending to draw the bead 41 against the edge of the opening 40 and thus extend the forearm. This extension of the forearm causes the edge of opening 28 to engage the bead 30 and draw the cable 27 downward relative to the sheath 34. This relative motion is facilitated by the decrease in distance between the termination 37 of the sheath 34 and the cable anchor 38 consequent upon the extension of the upper arm.

In the event that the forearm is flexed without raising the upper arm, as for example, if the forearm strikes an object while swinging backward, the bead 30 tends to remain in its position while the forearm flexes away from it. If the bead 30 were anchored to the forearm at the opening 28 this motion would tend to compress and kink the cable 27. However, the forearm being hollow, the bead 30 and cable 27 merely feed into the hollow space 29 and the cable 27 is not

kinked. A similar action occurs, upon occasion, with the lost motion connection between the extensor cable 39 and the forearm. In the event that the sphere 17 is made as a solid member, openings are provided in it to perform the lost motion function of the hollow space 29.

Fig. 8 illustrates a modification having a solid elbow ball 317. The cable 327 with its bead 330 and the cable 339 with its bead 341 are linked to the forearm with lost motion provided by the openings 361 and 362, respectively. These can be made conveniently by drilling holes through the forearm with a conventional tapered-point drill taking care that the proximal ends of the holes, such as 363, are large enough to allow the cables to pass through but small enough to restrain the beads. The distal ends of the holes may be plugged as at 364.

Although the particular modification of the invention illustrated in Fig. 1 shows the socket member of the elbow joint integral with the portion 10 of the upper arm and shows the ball member 17 integral with the forearm 16, nevertheless the elbow joint is readily adapted for manufacture as a separate unit easily installed in existing prior art arms. Such a unit is illustrated in Fig. 4 wherein the socket member 10a is made as a separate piece joined, as by a plurality of screws 49, to the lower end 10b of the conventional bucket member. Openings 50 in the member 10a are provided for a screw driver to reach the screws 42. Similarly, the ball member 17a is made as a separate piece adapted to be fastened, as by screws 51, with a lap joint to a conventional prior art forearm 16a. This type of construction offers the additional advantage of adjustability. Frequently, a bucket after use beyond the fitting period will adapt itself to the wearer by rotating about the longitudinal axis of the stump to a final permanent location different from its position when originally fitted. This causes undesirable pronation or supination of the upper arm, forearms and hand. With the elbow joint made as a detachable unit, this rotation is easily compensated for by merely unscrewing the socket member 10a from the bucket, turning it, with the forearm attached, sufficiently to counteract the rotation of the bucket and screwing it back onto the bucket at the new position.

While I have shown but certain embodiments of my invention, it is susceptible to further modification without departing from the spirit of the invention, I do not wish therefore, to be limited by the disclosures set forth, but only by the scope of the appended claims.

I claim:

1. In a prosthesis for an arm amputated above the elbow having a harness, an upper arm mem-

ber including a bucket, and a forearm member, a ball and socket elbow joint including a generally spherical socket portion at the distal end of said upper arm member, a generally spherical ball portion on the proximal end of said forearm member pivoted about the elbow axis to said upper arm member and in engagement with the socket of said socket portion, said upper arm member having a bore therethrough extending generally supra-laterally from an entrance opening on the anterior aspect thereof adjacent the intersection of an anterior-posterior longitudinal mid-plane with the anterior surface of said socket to an exit opening on the lateral aspect of said upper arm member, a flexible cable sheath lying in said bore and emerging from said exit opening and anchored to said upper arm member at a point superior of said exit opening, a flexible cable having a lost motion connection at its distal end with said ball portion and passing over the anterior surface of said ball portion along a great circle path defined by said mid-plane and passing through said sheath, and means anchoring the proximal end of said cable to said harness at a point adjacent the spine of the scapula of the amputated arm.

2. A prosthetic appliance for an arm having a ball and socket elbow joint comprising an upper arm member having a socket formed therein, a substantially hollow forearm member including a ball pivoted to said upper arm member about the elbow axis and engaging said socket, an opening into said forearm member, a substantially inextensible cable having an end extending through said opening into said forearm member, means on said end of said cable to prevent withdrawal of said end through said opening, means on said upper arm guiding said cable generally superiorly relative to said upper arm, said cable passing over the surface of said ball on a circle thereof lying in a plane normal to said elbow axis, and means to anchor said cable adjacent the shoulder of said arm.
